ATTORNEY

UNITED STATES PATENT OFFICE.

GEORGE F. HUTTON, OF STOCKTON, CALIFORNIA.

PORTABLE SHOWER BATH.

Application filed August 15, 1922. Serial No. 581,989.

To all whom it may concern:

Be it known that I, GEORGE F. HUTTON, a subject of Great Britain, residing at Stockton, county of San Joaquin, State of California, have invented certain new and useful Improvements in Portable Shower Baths; and I do declare the following to be a full, clear, and exact description of the same, reference being had to the accompanying drawings, and to the characters of reference marked thereon, which form a part of this application.

This invention relates to improvements in shower-baths, the principal object of the invention being to provide a portable device especially arranged to be placed alongside an ordinary bath tub so that the shower overhangs the tub, and provided with means for enabling it to be firmly yet detachably clamped to the rim of the tub.

By reason of the portability of the device, it is not only suitable for use in ordinary residence bathrooms not equipped with a fixed shower, but also for hotels and the like, since it enables a comparatively few of the devices being kept on hand, and sent up temporarily to the bath rooms of any patron desiring to take shower baths without the necessity of equipping all the baths with fixed showers, some of which might never be used.

I have also provided the device with adjustment features to adapt a single model for clamping to bathtubs of different heights from the floor, and to also allow the user to adjust the height of the shower nozzle to suit his fancy. The device is also self-supporting without the bath tub, so that it may be set up on any floor or elsewhere as an independent member, wherever a supply of water is available.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views:

Fig. 1 is a view of the portable shower bath as clamped to an ordinary bathtub.

Fig. 2 is an enlarged view of the lower portion of the device, detached from the tub.

Fig. 3 is a fragmentary section of the water-connection construction.

Referring now more particularly to the characters of reference on the drawings, the numeral 1 denotes a base pad of suitable size and preferably somewhat heavy, fixed on and projecting upwardly from which is a hollow standard 2 in which is slidably and rotatably mounted a post 3, held in any desired position by a set-screw 4 on the standard.

Fixed on top of the post 3, which is tubular for the sake of lightness but plugged at its upper end, as shown at 5 in Fig. 3, is a Y-bend or lateral pipe fitting 6, to the angled member of which a hose 7 is connected, this hose being adapted to be detachably connected at its other end to the faucet of a bath tub or other suitable water supply pipe.

Extending up from the member 6 a certain distance is a pipe structure 8 terminating in a horizontal portion 9 depending from and connected to the outer end of which is a spray nozzle 10 of any desired type.

Fixed to the structure 8 and projecting therefrom in a horizontal plane adjacent that of the spray and concentric therewith is a hoop 11 from which a waterproof curtain 12 of the kind commonly used for this purpose depends to a point somewhat short of the base.

The length of the horizontal pipe member 9 from the pipe 8 and post 3, of which said pipe is a continuation, is such that if the post is positioned alongside an ordinary bathtub, the center of the spray 10 will be about in line with the vertical longitudinal center line of the tub.

Owing to the size and weight of the base 1, the device is self supporting, but in order to enable it to be rigidly yet detachably connected to the tub, I have provided a novel yet simple form of clamping means.

This comprises a sleeve 13 slidably mounted on the standard 2 and adapted to be held at any desired level by a set-screw 14.

Projecting from the opposite sides of the sleeve are horizontal pins 15 on which are pivoted lever members 16 which converge at one end beyond the sleeve to form a handle 17. The opposite ends of the members 16, beyond the sleeve, are bent upwardly and toward the handle in the form of U shaped hooks as shown at 18, on the outer ends of which are pivoted downwardly projecting

clamp-arms 19 provided adjacent their lower ends with arch shaped portions 20 adapted to fit under the roll or rim 21 commonly provided around ordinary bath 5 tubs 22.

To operate this clamping device, the sleeve 13 is adjusted for height so that when the handle 17 is in its uppermost position, which position is fixed by reason of stop means 23 10 between the lever members and sleeve, the members 20 will just pass under the roll 21, the standard 2 being first placed adjacent the latter.

The handle 17 is then depressed, which of 15 course raises the portions 18, causing the arches or hooks 20 to seize the rim 21.

The pivotal connections of the members 16 with the sleeve and with the members 19 are so arranged with respect to each other 20 that when the handle is fully depressed the pivotal connections of the members 19 with the levers will be moved beyond the vertical line of the pins 15, or past the dead center point, as seen in Fig. 1 thus preventing un- 25 desired return movement of the handles.

The actual action set up by the operation of the clamping device is a downward pressure on the standard and base and an upward or lifting pressure on the tub, but as 30 the floor prevents downward movement of the base and the tub is prevented from upward movement by reason of its being fastened to the floor, the real result obtained is a firm clamping of one member to the other.

35 From the foregoing description it will be readily seen that I have produced such a device as substantially fulfills the objects of the invention as set forth herein.

While this specification sets forth in de- 40 tail the present and preferred construction of the device, still in practice such deviations from such detail may be resorted to as do not form a departure from the spirit of the invention, as defined by the appended 45 claims.

Having thus described my invention, what I claim as new and useful and desire to secure by Letters Patent is:

1. A portable shower bath structure com- 50 prising a base, a standard thereon, a post slidably mounted in the standard, and having a spray nozzle at its upper end, hand op- 55 erated lever means pivoted with respect to the standard, and members shaped to con- form to the underside of the rim of a bath- 60 tub depending from one end of the lever means.

2. A portable shower bath structure com-

prising a base, a standard thereon, a post 60 slidably mounted in the standard and hav- 65 ing a spray nozzle at its upper end, hand- 70 operated lever means pivoted with respect to the standard, an operating handle on one 75 end of said means and clamping members shaped to conform to the underside of the 80 rim of a bath tub pivoted to and depending from the opposite end of said lever means, and adapted to frictionally engage said rim when the handle is depressed; the pivots of 85 the clamping members and of the lever structure being so arranged with respect to each other that the clamping member pivots may be moved beyond the vertical plane of 90 the lever pivots in the direction away from the tub when the clamps are engaged. 95

3. A portable shower bath structure comprising a base, a standard mounted thereon, a spray nozzle supported by the standard, a hand lever pivotally mounted intermediate its ends with respect to the standard, and clamping means shaped to conform to the underside of the rim of a bathtub pivoted to and depending from one end of the lever. 100

4. A portable shower bath structure comprising a base, a standard mounted thereon, a spray nozzle supported by the standard, a sleeve slidably and adjustably mounted on the standard, a lever pivoted intermediate its ends on the sleeve for movement in a vertical plane, and clamping means shaped to conform to the underside of the rim of a bathtub depending from one end of the lever; said clamping means being adapted to be raised into engagement with the rim with the downward movement of the opposite end 95 of the lever.

5. A portable shower bath structure comprising a base to rest on the floor, a standard mounted on the base and supporting a spray nozzle, clamping means for engaging the rim of a bathtub mounted on the standard, and means for causing the clamping means to frictionally engage said rim and the base to be pressed against the floor. 100

6. A portable shower bath structure comprising a base to rest on the floor, a standard mounted on the base and supporting a spray nozzle, clamping means shaped to engage the underside of the rim of a bathtub mounted on the standard, and means for forcing 110 said clamping means upwardly into engagement with said rim whereby at the same time the pressure of the base against the floor will be increased.

In testimony whereof I affix my signature.
GEORGE F. HUTTON.
